FIG. 1 is a top view of a molded plastic container, with the cover thereon, showing my design;

FIG. 2 is a bottom view thereof;

FIG. 3 is a side view of one of the long sides thereof with the cover thereon;

FIG. 4 is a side view of one of the short sides thereof with the cover thereon; and

FIG. 5 is a sectional view taken through line 5—5 of FIG. 3.

The sides not shown are the same as the sides shown in the drawings.

I claim:

The ornamental design for a molded container and cover therefor, substantially as shown and described.
